US00D511341S

(12) **United States Design Patent** (10) Patent No.: **US D511,341 S**
Chen (45) Date of Patent: **** Nov. 8, 2005**

(54) **DIGITAL TRANSMISSION DEVICE**

(75) Inventor: **Chih-Kang Chen, Miao-Li Hsien (TW)**

(73) Assignee: **Lite-On Technology Corp., Taipei (TW)**

(**) Term: **14 Years**

(21) Appl. No.: **29/219,111**

(22) Filed: **Dec. 14, 2004**

(30) **Foreign Application Priority Data**

Sep. 29, 2004 (TW) 93305729

(51) LOC (8) Cl. **14-03**

(52) U.S. Cl. **D14/240**

(58) Field of Search D14/240, 242, D14/299, 140, 155, 230, 236; D13/123, 184, 199; 361/600, 728, 730, 622, 641; 455/3.01, 3.06, 553.1; 379/900, 908, 441, 67.1, 219-220.01

(57) **CLAIM**

The ornamental design for a digital transmission device, as shown and described.

DESCRIPTION

FIG. 1 is a front view of a digital transmission device showing our new design;
FIG. 2 is a rear view thereof;
FIG. 3 is a left view thereof;
FIG. 4 is a right view thereof;
FIG. 5 is a top plan view thereof;
FIG. 6 is a bottom plan view thereof; and,
FIG. 7 is a perspective view thereof.
